UNITED STATES PATENT OFFICE.

WALTER ALLEN COMPTON, OF COLUMBUS, OHIO.

BOILER-TUBE.

No. 878,353.

Specification of Letters Patent.

Patented Feb. 4, 1908.

Application filed June 11, 1906, Serial No. 321,225. Renewed June 24, 1907. Serial No. 380,543.

To all whom it may concern:

Be it known that I, WALTER A. COMPTON, a citizen of the United States, residing at Columbus, in the county of Franklin and State of Ohio, have invented certain new and useful Improvements in Boiler-Tubes; and I do declare the following to be a full, clear, and exact description of the invention, such as will enable others skilled in the art 10 to which it appertains to make and use the same.

This invention relates to improvements in boiler tubes.

The object of the invention is to provide 15 means whereby a boiler tube may be fastened in the tube sheets in such a manner that leaking around the joints from the contraction of the tubes will be prevented.

A further object is to provide a boiler tube 20 having means whereby the contraction and expansion of the tube will be prevented from breaking or injuring the same or any of the parts connected therewith.

With the above and other objects in view, 25 the invention consists of certain novel features of construction, combination and arrangement of parts, as will be hereinafter described and claimed.

In the accompanying drawings:—Figure 1 30 is a longitudinal sectional view through a portion of the boiler tube sheets and a boiler tube constructed in accordance with the invention; Fig. 2 is a rear side view of the back tube sheet and the outer end or head 35 of the boiler tube bushing; Fig. 3 is a detail side view of the boiler tube bushing; and Fig. 4 is a perspective view of the copper gasket or sleeve on the front end of the tube.

Referring more particularly to the drawings, 40 1 denotes the front tube sheet, and 2 denotes the rear tube sheet of a fire tube boiler.

3 denotes one of the boiler tubes, which is arranged in the front tube sheet in the usual 45 manner and is provided with an annular flange or bead 4, which is adapted to engage the outer side of the front tube sheet, as shown. The rear end of the tube 3 is threaded interiorly for a suitable distance, 50 as at 5, and into said threaded end is adapted to be screwed a bushing 6 which is also screwed through a threaded alined aperture 7 in the rear tube sheet 2. The bushing 6 is provided on its outer end with an 55 annular radially-projecting flange or bead 8

which is adapted to engage the outer side of the rear tube sheet, as shown. The bushing 6 is provided with an inwardly-tapered bore in the outer end of which is arranged inwardly-projecting lugs or ribs 9. The 60 lugs or ribs 9 facilitate the engagement of a socket wrench with said bushing, whereby the latter is screwed through the tube sheet and into the end of the boiler tube, as will be understood.

Arranged on the bushing 6 between the inner side of the rear tube sheet 2 and the adjacent end of the boiler tube is a copper washer 10, which when the bushing is tightly screwed into the tube is jammed between the end of the latter and the tube sheet, thus protecting the threads of the bushing and forming a steam and water tight joint for the same. Arranged on the forward end of the boiler tube and in the 70 hole or aperture of the tube sheet through which the tube passes is a copper sleeve or gasket 12, the object of which is to permit the tube 3 to expand and contract, thereby removing the strain from the bushing, thus 75 preventing the breaking of the threads or the flange on said bushing or the flange on the opposite end of the tube. Said sleeve or gasket also prevents any leaking at the front 80 end of the tube due to the contraction of the 85 same.

By providing a bushing for the end of the boiler tube and arranging the same as herein shown and described the end of the boiler tube will be entirely within the boiler and 90 protected from contact with the cold air when the fire box door is opened, thus preventing sudden cooling and contracting of the boiler tubes.

The great expansive qualities of the copper washer 10 and the copper sleeve or gasket 12 serves to form water and steam-tight joints 95 between the parts engaged thereby.

From the foregoing description, taken in connection with the accompanying drawings, 100 the construction and operation of the invention will be readily understood without requiring a more extended explanation.

Various changes in the form, proportion and the minor details of construction may be 105 resorted to without departing from the principle or sacrificing any of the advantages of this invention, as defined by the appended claims.

Having thus described my invention, what 110

I claim as new and desire to secure by Letters-Patent, is:—

1. The combination with the front and rear tube sheets of a boiler having therein 5 alined boiler tube passages, of a boiler tube adapted to be inserted through the passage in said front tube sheet, an annular flange on the forward end of said tube to engage the outer side of said tube sheet, a hollow ex-10 teriorly threaded bushing adapted to be screwed through the passage in the rear tube sheet and into the threaded rear end of said tube, an annular flange or bead formed on the outer end of said bushing to engage the 15 outer sides of said rear tube sheet, a sleeve or gasket arranged on the forward end of said tube and passing through the aperture in the front tube sheet, and around the flange on said forward end of the tube, and a washer 20 arranged between the rear end of the tube and the adjacent side of the rear tube sheet, substantially as described.
2. The combination with the front and rear tube sheets, of a boiler having therein 25 alined boiler tube passages, of a boiler tube adapted to be inserted through the passage

in said front tube sheet, an annular flange on the forward end of said tube to engage the outer side of said tube sheet, a hollow, exteriorly threaded bushing adapted to be 30 screwed through the passage in the rear tube sheet and into the threaded rear end of said tube, an annular flange or bead formed on the outer end of said bushing to engage the outer sides of said rear tube sheet, lugs or 35 ribs formed on the inner wall of said hollow bushing to facilitate the engagement of a wrench therewith, a sleeve or gasket arranged on the forward end of said tube and passing through the aperture in the front 40 tube sheet, and around the flange on said forward end of the tube and a washer arranged between the rear end of the tube and the adjacent side of the rear tube sheet, substantially as described. 45

In testimony whereof I have hereunto set my hand in presence of two subscribing witnesses.

WALTER ALLEN COMPTON.
